ELECTRICAL CONTROL APPARATUS

Arthur E. Dedd, Edgewood, Pa., assignor to The Union Switch & Signal Company, Swissvale, Pa., a corporation of Pennsylvania

Original application December 23, 1941, Serial No. 424,151, now Patent No. 2,324,200, dated July 13, 1943. Divided and this application November 11, 1942, Serial No. 465,183

10 Claims. (Cl. 246—219)

My invention relates to electrical control apparatus and particularly to apparatus for effecting one function when a control circuit is energized by current of one relative polarity and another function when the control circuit is energized by current of the other relative polarity.

This application is a division of my application Serial No. 424,151, filed December 23, 1941, for Electrical control apparatus, now Patent No. 2,324,200 dated July 13, 1943.

In my application identified above there is shown control apparatus employing a polar relay and a biased polar relay energized from a polarized control circuit. The apparatus shown in that application is arranged so that in each position of the polar contacts of the polar relay, the winding of the polar relay is connected across the control wires through an asymmetric unit poled to permit flow of energy of a polarity effective to cause movement of the relay contacts to their other position. The apparatus shown in that application is also arranged so that in each position of the polar contact of the polar relay the winding of the polar relay is connected across the control wires in series with the winding of a biased polar relay so that the biased polar relay checks correspondence between the position of the polar relay contacts and the polarity of the energy supplied to the control circuit.

In some situations a larger number of contacts are required than can be provided on a single biased polar relay.

An object of this application is to provide apparatus of the type shown in my original application but arranged so that the winding of the polar relay is connected in series with one biased polar relay in one position of the polar relay contact and is connected in series with a different biased polar relay in the other position of the polar relay contact.

Other objects of the invention and features of novelty will be apparent from the following description taken in connection with the accompanying drawing.

I shall describe three forms of apparatus embodying my invention and shall then point out the novel features thereof in claims.

In the drawing, Fig. 1 is a diagram illustrating one embodiment of my invention, and

Figs. 2 and 3 are diagrams showing modifications of the invention adapted to indicate the position of a track switch and to check correspondence between a switch control relay and a switch indication relay.

Referring to Fig. 1 of the drawing, the reference character P designates a polar relay, while the reference characters NA and NB designate

auxiliary relays. The windings of the relays P, NA and NB are energized over a polarized control circuit here shown as comprising conductors 10 and 11 which are connected by contacts of a pole changer PC with a suitable source of direct current, such as a battery, the terminals of which are designated + and -. The conductors 10 and 11 may be line wires, or they may be the track rails of a section of railway track, while the pole changer PC may be a manually operated device, it may be the contacts of a relay, or it may be any other suitable mechanism.

The relay P has associated therewith a rectifier unit consisting of rectifier elements K1 and K2 which are connected in series and are both poled to permit energy to flow in the same direction.

The auxiliary relays NA and NB are preferably, but not necessarily, of the biased polar type, and each is arranged so that its contacts become picked up only when the positive terminal of the source is connected to the left-hand or first terminal of the relay winding. One form of relay which may be employed for this purpose is shown in Letters Patent of the United States No. 2,057,605 granted October 13, 1936 to Herman G. Blosser.

The relay P is of the polar stick type being constructed in such manner that the relay contacts when moved to either position remain in that position until energy of the polarity effective to move the relay contacts to their other position is supplied to the relay winding.

The equipment is shown in the condition it assumes when energy of normal polarity is supplied to the control wires 10 and 11, and the contacts 13 and 14 of polar relay P are in their left-hand or normal positions. At this time energy flows from the positive terminal of the source through control wire 11, winding of relay P, and contact 14 to the left-hand or first terminal of the rectifier unit and also to the left-hand or first terminal of the winding of relay NA, through this winding, contact 13 of relay P, and control wire 10 to the negative terminal of the source. Accordingly, the contact 15A of relay NA is picked up, while the circuit of relay NB is interrupted and the contact 15B is released. The contacts 15A and 15B may be employed in any desired manner for any appropriate purpose.

On movement of the contacts of the pole changer PC the supply of energy to the relay NA is interrupted and the relay contacts release.

When the contacts of the pole changer are moved to their reverse positions the positive terminal of the source is connected to control wire 10, and energy flows from this wire through rectifier K1, contact 14, winding of relay P, and

control wire 11 to the negative terminal of the source. This energy causes the contacts of relay P to shift to their right-hand or reverse positions so that the windings of relays P and NB are energized in series over the circuit which is traced from the positive terminal of the source through control wire 10, and right-hand polar contact 13 of relay P to the left-hand or first terminal of the winding of relay NB, through this winding, contact 14 of relay P, winding of relay P, and control wire 11 to the negative terminal of the source. The energy in the winding of relay NB, therefore, flows in the proper direction to pick up the relay contact, while the energy in the winding of relay P is effective to maintain the contacts 13 and 14 in their right-hand or reverse positions.

On subsequent movement of the contacts of the pole changer PC away from their reverse positions the supply of energy to the winding of relay NB is interrupted and the relay contacts release.

When the contacts of the pole changer PC are moved to their normal positions energy of normal polarity is supplied to the relay P over the circuit which is traced from the positive terminal of the source through control wire 11, winding of relay P, right-hand or reverse contact 14, rectifier K2, and control wire 10 to the negative terminal of the source. This energy causes the contacts of the relay P to move to their normal or left-hand positions, while when the contacts 13 and 14 are in their normal positions the windings of relays P and NA are energized in series over the circuit traced above so that the contact 15A of relay NA is picked up.

If the supply of energy over the control wires is interrupted the contacts of both relays NA and NB will be released.

In the system shown in Fig. 1 the rectifiers K1 and K2 prevent energization of the relays NA and NB by current of the wrong polarity, while the system operates to check the circuits of the rectifiers to see that these circuits are intact.

If desired the relays NA and NB may each have a rectifier, not shown, connected across its terminals as shown in Fig. 3 to increase the release period of the relay, and to provide increased protection against energization of the relay by energy of the wrong polarity.

The system shown in Fig. 1 of the drawing is adapted for use in a switch indication circuit to indicate the position of a track switch and to also indicate when the switch control relay and the switch indication relay associated with a railway track switch are in correspondence, and Fig. 2 is a diagram showing this application of the invention.

Referring to Fig. 2 there is shown therein a track switch W which is movable between a normal and a reverse position by a switch machine SM. The machine SM may be of any appropriate construction and is controlled by a polarized switch control relay WR, which in turn is controlled by a control lever L. The switch has associated therewith contacts 20 and 21 which are governed in accordance with the position of the switch, and control the supply of energy to the relay P and to the auxiliary relays NA and NB, while the circuits of these relays are controlled by neutral and polar contacts of relay WR.

The system shown in Fig. 2 employs a rectifier unit similar to that shown in Fig. 1 and consisting of rectifier elements K1 and K2.

The equipment is shown in the condition which

it assumes when the control lever L and the switch W are in their normal positions. As lever L is in its normal position energy of normal polarity is supplied to the relay WR and its neutral contact 24 is picked up, while its polar contact 25 is in its left-hand or normal position so that a circuit for the switch machine SM is established to cause the switch W to be moved to its normal position and to be maintained there.

As the switch W is in its normal position the contact 20 establishes connection from the positive terminal of a source to indication wire 26, while contact 21 establishes connection from the negative terminal of the source to indication wire 28 with the result that energy of normal polarity is supplied to the wires 26 and 28. As the contact 14 of relay P is in its normal or left-hand position, and as the polar contact 30 of relay WR is in its left-hand or normal position and the neutral contact 31 of relay WR is picked up, the relays P and NA are energized in series over the circuit which is traced from the positive terminal of the source through contact 20, wire 26, winding of relay P, contact 14, and wire 33 to the first terminal of the rectifier unit, winding of relay NA, contacts 30 and 31 of relay WR to the intermediate terminal of the rectifier unit, wire 28, and contact 21 to the negative terminal of the source. The positive terminal of the source is connected to the left-hand or first terminal of the winding of relay NA so that the direction of flow of energy in this winding is proper to pick up the relay contact 15A, and this contact is picked up and may establish a circuit to permit clearing of signals appropriate for movement of traffic in the normal position of the switch.

When the lever L is moved to its reverse position energy of reverse polarity is supplied to the relay WR and its polar contacts 25 and 30 move to their right-hand or reverse positions.

On this movement of contact 25 a circuit for the switch machine SM is established to cause this machine to move the switch to its reverse position, while on this movement of contact 30 the circuit traced above for energizing the relay NA is interrupted.

When the switch W completes its movement to its reverse position contact 20 connects the positive terminal of the source to wire 28 and contact 21 connects the negative terminal of the source to wire 26 with the result that energy is supplied to relay P over the circuit which is traced from the positive terminal of the source over wire 28, through rectified K1, wire 33, normal polar contact 14, winding of relay P, and control wire 26 to the negative terminal of the source. This energy causes the contact of relay P to move to its right-hand or reverse position, and when this contact is in this position the windings of relays P and NB are energized in series over the circuit which is traced from the positive terminal of the source through contact 20, and wire 28 to the intermediate terminal of the rectifier unit, and contacts 31 and 30 of relay WR to the left-hand or first terminal of the winding of relay NB, through this winding to the second terminal of the rectifier unit, wire 34, right-hand contact 14, winding of relay P, wire 26, and contact 21 to the negative terminal of the source. As energy flows through the winding of relay NB from its left-hand or first terminal to its right-hand or second terminal this energy is effective to pick up the contact 15B of the relay. This contact may establish a circuit to

permit clearing of signals appropriate when the switch is in its reverse position.

On subsequent movement of the switch control lever L to its normal position energy of normal polarity is supplied to the relay WR and its contacts 25 and 30 shift to their left-hand or normal positions. On this movement of contact 25 the circuit for causing the switch machine SM to move the switch from its reverse to its normal position is established, while on this movement of contact 30 the circuit of the relay NB is interrupted.

When the switch W completes its movement to its normal position the contacts 20 and 21 establish the circuit to supply energy of normal polarity to the wires 26 and 28, and the relay P is energized over the circuit which is traced from the positive terminal of the source through contact 20, wire 26, winding of relay P, right-hand polar contact 14 of relay P, wire 34, rectifier K2, wire 28, and contact 21 to the negative terminal of the source. This energy causes the contact 14 to shift to its left-hand or normal position, and when the contact is in this position the relays P and NA are energized in series over the circuit traced above.

The system provided by this modification is arranged so that if the contacts of the switch control relay WR and of the relay P are out of correspondence the relays NA and NB will both be released, while these relays will also be released if the energy supplied to the wires 26 and 28 is not of the proper polarity.

The system provided by this modification is also arranged so that continuity of the circuits through the rectifiers is checked so that failure of the rectifiers will be promptly detected.

The modification shown in Fig. 2 is arranged so that interruption of the supply of energy to the wires 26 and 28 for any reason, such as failure of the switch to complete its movement, will result in deenergization of both of the relays NA and NB. In addition, this modification is arranged so that when the switch control relay WR is deenergized its neutral contact 34 is released and prevents energization of relay NA or NB.

In Fig. 3 of the drawing there is shown another modification of the invention which may be employed to indicate correspondence between a switch control relay and a switch indication relay.

The modification shown in Fig. 3 employs auxiliary relays NA and NB, while it employs a rectifier unit consisting of rectifier elements K5 and K6 which are connected in series and are both poled to permit energy to flow from the right-hand or second terminal of the unit to the left-hand or first terminal of the unit.

The equipment of Fig. 3 is shown in the condition which it assumes when switch control lever L is in its normal position, the contacts of switch control relay WR and switch indication relay P are in their normal positions, and the switch W is in its normal position.

As the switch W is in its normal position the switch operated contacts 28 and 21 supply energy of normal polarity to the indication wires 26 and 28 so that relays P and NA are energized by current supplied over the circuit which is traced from the positive terminal of the source through contact 20, wire 26, winding of relay P, and left-hand contact 14 of relay P to the left-hand or first terminal of the rectifier unit, front neutral contact 31 and left-hand polar contact 30 of relay WR to the left-hand or first

terminal of the winding of relay NA, through the winding of relay NA, left-hand contact 36 of relay P to the right-hand or second terminal of the rectifier unit, through rectifier K5, wire 28, and contact 21 to the negative terminal of the source. Accordingly, contact 15A of relay NA is picked up.

On movement of the control lever L to its reverse position energy of reverse polarity is supplied to the switch control relay WR and its polar contacts shift to their right-hand or reverse positions with the result that contact 25 establishes the circuit to cause the switch machine SM to move the switch W to its reverse position.

15 In addition, at this time contact 30 of relay WR
interrupts the circuit traced above for energizing
the relay NA and the contacts of this relay
release.

When the switch W is moved to its reverse position contacts 20 and 21 cause energy of reverse polarity to be supplied to wires 26 and 28 and energy is supplied to relay P over the circuit which is traced from the positive terminal of the source through contact 20, wire 28, rectifier K6, left-hand polar contact 14 of relay P, winding of relay P, wire 26, and contact 21 to the negative terminal of the source.

The energy supplied to the relay P over this circuit causes the contacts of the relay to shift to their right-hand or reverse positions so that the circuit traced above is interrupted, and a circuit is established to energize the relays P and NB in series. This circuit is traced from the right.

series. This circuit is traced from the positive terminal of the source through contact 20, wire 35 28, rectifier K6, front neutral contact 31 and right-hand polar contact 30 of relay WR to the right-hand or first terminal of the winding of relay NB, through this winding, right-hand contacts 36 and 14 of relay P, winding of relay P

40 wire 26, and contact 21 to the negative terminal of the source. In this modification the relay NB is arranged so that its contact becomes picked up only when energy flows through the relay winding from the right-hand terminal to the left-hand terminal thereof. It will be seen that the direction of flow of energy through the winding of relay NB at this time is proper to pick up the relay contacts, and accordingly, the contact 15B picks up, and may establish a circuit to permit clearing of a signal appropriate for the reverse position of the switch.

On a subsequent movement of the control lever L to its normal position the contacts of the relay WR shift to their left-hand or normal positions so that contact 25 establishes the circuit to cause the switch machine SM to move the switch W to its normal position.

In addition, at this time contact 30 of relay WR interrupts the circuit traced above for energizing the relay NB and the contacts of this relay release.

When the switch W completes its movement to its normal position the switch operated contacts 20 and 21 establish connections to supply energy of normal polarity to the indication wires 26 and 28 and this energy is supplied to the relay P over the circuit which is traced from the positive terminal of the source through contact 20, wire 26, winding of relay P, right-hand contact 14 of relay P, rectifier K5, wire 28, and contact 21 to the negative terminal of the source.

The energy supplied to the relay F causes the contacts of this relay to shift to their left-hand or normal positions, and when the relay contacts are in this position they establish the circuit

traced above to energize the relays NA and P in series.

The system provided by this modification of the invention is arranged so that the integrity of the rectifiers K5 and K6 is checked and failure of either of these rectifiers will be promptly detected.

This modification is also arranged so that the relays NA and NB cannot be energized if the contacts of relays WR and P are out of correspondence, while rectifiers K7 and K8 may be connected across the terminals of the relays NA and NB to prevent energization of these relays, if energy of the wrong polarity is supplied to the indication wires.

Although I have herein shown and described several forms of electrical control apparatus embodying my invention, it is understood that various changes and modifications may be made therein within the scope of the appended claims without departing from the spirit and scope of my invention.

Having thus described my invention, what I claim is:

1. In combination, a control circuit comprising a first and a second conductor to which energy of one polarity is supplied at times and to which energy of the other polarity is supplied at other times, a polar relay connected in series with one of said conductors and having a contact movable to one position or another according as energy of one polarity or the other is supplied to the relay winding, a rectifier unit comprising a first and a second rectifier element connected in series between a first and a second terminal and both poled to permit energy to flow from said second to said first terminal, said unit also having an intermediate terminal between said rectifier elements, the first conductor being connected to the intermediate terminal of said rectifier unit, the contact of said polar relay being effective when in the position which it occupies when the positive terminal of the source is connected to the first conductor to connect said second conductor to the second terminal of said rectifier unit and being effective when in the position which it occupies when the positive terminal of the source is connected to the second conductor to connect said second conductor to the first terminal of said rectifier unit, a first and a second auxiliary relay, means for connecting one terminal of the winding of the first auxiliary relay to the first terminal of the rectifier unit and for connecting the other terminal of the winding of said first auxiliary relay to the intermediate terminal of said rectifier unit, means for connecting one terminal of the winding of the second auxiliary relay to the intermediate terminal of said rectifier unit and for connecting the other terminal of the winding of said second auxiliary relay to the second terminal of said rectifier unit, a circuit controlled by a contact of said first auxiliary relay, and a circuit controlled by a contact of said second auxiliary relay.

2. In combination, a control circuit comprising a first and a second conductor to which energy of one polarity is supplied at times and to which energy of the other polarity is supplied at other times, a polar relay connected in series with one of said conductors and having a contact movable to one position or another according as energy of one polarity or the other is supplied to the relay winding, a rectifier unit comprising a first and a second rectifier element connected in series between a first and a second terminal and both poled to permit energy to flow from the second to the first terminal, said unit also having an intermediate terminal between said rectifier elements, a polar indication relay having its winding connected in series with one of said indication conductors, one of said indication conductors being connected to the intermediate terminal of the rectifier unit, a contact of the polar indication relay being effective according as it is in one or the other of its positions to connect the other indication conductor to the first or second terminal of said rectifier unit, the equipment being arranged so that the polar indication relay contact connects said other conductor to the first or second terminal of the rectifier unit according as said contact is in the position to which it is moved when the relay is energized by current of the polarity in which

poled to permit energy to flow from said second to said first terminal, said unit also having an intermediate terminal between said rectifier elements, the first conductor being connected to the intermediate terminal of said rectifier unit, the contact of said polar relay being effective when in the position which it occupies when the positive terminal of the source is connected to the first conductor to connect said second conductor to the second terminal of said rectifier unit and being effective when in the position which it occupies when the positive terminal of the source is connected to the second conductor to connect said second conductor to the first terminal of said rectifier unit, a first and a second auxiliary relay each having a winding having a first and a second terminal and each having a normally released contact which becomes picked up only when energy flows through the relay winding from the first to the second terminal thereof, means for connecting the first terminal of the winding of the first auxiliary relay to the first terminal of said rectifier unit and for connecting the second terminal of the winding of said first auxiliary relay to one of the other terminals of said rectifier unit, means for connecting the second terminal of the winding of the second auxiliary relay to the second terminal of said rectifier unit and for connecting the first terminal of the winding of said second auxiliary relay to one of the other terminals of said rectifier unit, a circuit controlled by a contact of said first auxiliary relay, and a circuit controlled by a contact of said second auxiliary relay.

3. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, an indication circuit comprising a first and a second conductor, means effective when the switch is in its normal position to supply to the indication circuit energy of a polarity in which the positive terminal of the source is connected to one of said conductors and effective when the switch is in its reverse position to supply to the indication circuit energy of a polarity in which the positive terminal of the source is connected to the other of said conductors, a rectifier unit comprising a pair of rectifier elements connected in series between a first and a second terminal and both poled to permit energy to flow from the second to the first terminal, said unit also having an intermediate terminal between said rectifier elements, a polar indication relay having its winding connected in series with one of said indication conductors, one of said indication conductors being connected to the intermediate terminal of the rectifier unit, a contact of the polar indication relay being effective according as it is in one or the other of its positions to connect the other indication conductor to the first or second terminal of said rectifier unit, the equipment being arranged so that the polar indication relay contact connects said other conductor to the first or second terminal of the rectifier unit according as said contact is in the position to which it is moved when the relay is energized by current of the polarity in which

the negative or the positive terminal of the source is connected to said one indication conductor, a first and a second auxiliary relay, means for connecting one terminal of the winding of the first auxiliary relay to the terminal of the rectifier unit to which the indication relay contact establishes connection when the relay is energized by current of the polarity which is supplied thereto when the switch is in its normal position, means for connecting the other terminal of the winding of the first auxiliary relay to one of the other terminals of the rectifier unit, means for connecting one terminal of the winding of the second auxiliary relay to the terminal of the rectifier unit to which the indication relay contact establishes connection when the relay is energized by current of the polarity which is supplied thereto when the switch is in its reverse position, means for connecting the other terminal of the second auxiliary relay to one of the other terminals of said rectifier unit, the circuits of the auxiliary relays being controlled by the polar contacts of the switch control relay so that the circuit of the first auxiliary relay is complete only when said polar contacts are in their normal position and so that the circuit of the second auxiliary relay is complete only when said polar contacts are in their reverse position, a circuit controlled by a contact of the first auxiliary relay, and a circuit controlled by a contact of the second auxiliary relay.

4. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, an indication circuit comprising a first and a second conductor, means effective when the switch is in its normal position to supply to the indication circuit energy of a polarity in which the positive terminal of the source is connected to one of said conductors and effective when the switch is in its reverse position to supply to the indication circuit energy of a polarity in which the positive terminal of the source is connected to the other of said conductors, a rectifier unit comprising a pair of rectifier elements connected in series between a first and a second terminal and both poled to permit energy to flow from the second to the first terminal, said unit also having an intermediate terminal between said rectifier elements, a polar indication relay having its winding connected in series with one of said indication conductors, one of said indication conductors being connected to the intermediate terminal of the rectifier unit, a contact of the polar indication relay being effective according as it is in one or the other of its positions to connect the other indication conductor to the first or second terminal of said rectifier unit, the equipment being arranged so that the polar indication relay contact connects said other conductor to the first or second terminal of the rectifier unit according as said contact is in the position to which it is moved when the relay is energized by current of the polarity in which the negative or the positive terminal of the source is connected to said one indication conductor, a first auxiliary

10 relay having one terminal of its winding connected to the first terminal of said rectifier unit and a second auxiliary relay having one terminal of its winding connected to the second terminal of said rectifier unit, and means effective according as the polar contacts of the switch control relay are in their normal or reverse positions to connect the intermediate terminal of said rectifier unit to the other terminal of the first or the second auxiliary relay.

5. In combination, a pair of conductors to which energy of normal polarity is supplied at times and to which energy of reverse polarity is supplied at other times, a polar relay having one terminal of its winding connected to one of said conductors, means including a normal polar contact of said polar relay for connecting the other terminal of the winding of said relay to said other conductor through a first asymmetric unit poled to permit flow of energy of reverse polarity and to also connect said other terminal of said polar relay winding to said other conductor in series with the winding of a first auxiliary relay, and means including a reverse polar contact of said polar relay for connecting the other terminal of the winding of said polar relay to said other conductor through a second asymmetric unit poled to permit flow of current of normal polarity and to also connect said other terminal of said polar relay winding to said other conductor in series with the winding of a second auxiliary relay.

6. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, a pair of indication conductors, means effective according as the switch is in its normal or its reverse position to supply to said indication conductors energy of normal or reverse polarity, a polar indication relay having one terminal of its winding connected to one of said indication conductors, means including a normal polar contact of said indication relay for connecting the other terminal of the winding of said indication relay to the other one of said indication conductors through an asymmetric unit poled to permit flow of energy of reverse polarity, means including a reverse polar contact of said indication relay for connecting the other terminal of the winding of said indication relay to the other one of said indication conductors through an asymmetric unit poled to permit flow of energy of normal polarity, means including a normal polar contact of said indication relay and a normal polar contact of said control relay for connecting said other terminal of the winding of said indication relay to said other indication conductor in series with the winding of a first auxiliary relay, means including a reverse polar contact of said indication relay and a reverse polar contact of said control relay for connecting said other terminal of the winding of said indication relay to said other indication conductor in series with the winding of a second auxiliary relay, a circuit controlled by a contact of said first auxiliary relay, and a circuit

controlled by a contact of said second auxiliary relay.

7. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, a pair of indication conductors, means effective according as the switch is in its normal or its reverse position to supply to said indication conductors energy of normal or reverse polarity, a polar indication relay having one terminal of its winding connected to one of said indication conductors, means including a normal polar contact of said indication relay for connecting the other terminal of the winding of said indication relay to the other one of said indication conductors through a first asymmetric unit poled to permit flow of energy of reverse polarity, means including a reverse polar contact of said indication relay for connecting the other terminal of the winding of said indication relay to the other one of said indication conductors through a second asymmetric unit poled to permit flow of energy of normal polarity, means including a normal polar contact of said control relay for connecting a first auxiliary relay in multiple with said first asymmetric unit, means including a reverse polar contact of said control relay for connecting a second auxiliary relay in multiple with said second asymmetric unit, a circuit controlled by said first auxiliary relay, and a circuit controlled by said second auxiliary relay.

8. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, a pair of indication conductors, means effective according as the switch is in its normal or its reverse position to supply to said indication conductors energy of normal or reverse polarity, a polar indication relay having one terminal of its winding connected to one of said indication conductors, means including a polar contact of said indication relay for connecting the other terminal of the winding of said indication relay to the other one of said indication conductors through a first asymmetric unit poled to permit flow of energy of reverse polarity, means including a reverse polar contact of said indication relay for connecting the other terminal of the winding of said indication relay to the other one of said indication conductors through a second asymmetric unit poled to permit flow of energy of normal polarity, means including normal polar contacts of said indication relay and of said control relay for connecting the winding of a first auxiliary relay in series with said second asymmetric unit and in multiple with said first asymmetric unit, means including reverse polar contacts of said indication relay and of said control relay for connecting the winding of a second

auxiliary relay in series with said first asymmetric unit and in multiple with said second asymmetric unit, a circuit controlled by said first auxiliary relay, and a circuit controlled by a contact of said second auxiliary relay.

9. In combination, a pair of conductors to which energy of normal polarity is supplied at times and to which energy of reverse polarity is supplied at other times, a polar relay having one terminal of its winding connected to one of said conductors, means including a first normal polar contact of said relay for connecting the other terminal of the winding of said relay to the other conductor through a first asymmetric unit poled to permit flow of energy of reverse polarity, means including a first reverse polar contact of said relay for connecting the other terminal of said relay to said other conductor through a second asymmetric unit poled to permit flow of energy of normal polarity, means including a second normal polar contact of said relay for connecting the other terminal of the winding of said relay to said other conductor in series with the winding of a first auxiliary relay, means including a second reverse polar contact of said polar relay for connecting the other terminal of the winding of said polar relay to said other conductor in series with the winding of a second auxiliary relay, a circuit controlled by a contact of said first auxiliary relay, and a circuit controlled by a contact of said second auxiliary relay.

10. In combination, a railway track switch, a machine for moving said switch between a normal and a reverse position, a polarized switch control relay to which energy of normal polarity is supplied at times and to which energy of reverse polarity is supplied at other times, said relay having polar contacts effective when in their normal position to cause the switch machine to move the switch to its normal position and effective when in their reverse position to cause the switch machine to move the switch to its reverse position, a pair of indication conductors, means effective according as the switch is in its normal or its reverse position to supply to said indication conductors energy of normal or reverse polarity, a polar indication relay having one terminal of its winding connected to one of said indication conductors, means including a normal polar contact of said indication relay for connecting the other terminal of the winding of said indication relay to the other one of said indication conductors through a first asymmetric unit poled to permit flow of energy of reverse polarity, means including said normal polar contact of said indication relay and a normal polar contact of said control relay for also connecting the other terminal of the winding of said indication relay to the other one of said indication conductors in series with the winding of a first auxiliary relay, means including a reverse polar contact of said indication relay for connecting the other terminal of the winding of said indication relay to the other one of said indication conductors through a second asymmetric unit poled to permit flow of energy of normal polarity, means including said reverse polar contact of said indication relay and a reverse polar contact of said control relay for also connecting the other terminal of the winding of said indication relay to the other one of said indication conductors in series with the winding of a second auxiliary relay, a circuit controlled by said first auxiliary relay, and a circuit controlled by said second auxiliary relay.
